INSEAM TRIMMING MACHINE

John M. Whelton, Peabody, Mass., assignor to
 United Shoe Machinery Corporation, Borough
 of Flemington, N. J., a corporation of New
 Jersey

Application March 5, 1940, Serial No. 322,361

7 Claims. (Cl. 12—82)

This invention relates to machines for trimming the inseams of welted shoes and is herein set forth as providing improvements in a machine of the same general type as that disclosed in United States Letters Patent 1,226,872, granted May 22, 1917, on application of Andrew Eppler.

The problem with which the invention is concerned is due to the fact that the thickness of the inseam is considerably greater at the toe end of a shoe than elsewhere. The greater thickness at the toe end is due in part to the pleats unavoidably formed in the toe-lasting operation and in part to the presence of two additional layers of material at the toe end, namely, a toe-box and a doubler.

The present exacting standards of shoemaking require trimming the inseam of a welted shoe as closely as possible to the stitches therein.

Considering that in a trimming machine of the type identified above the shoe is presented upside down to the trimming cutter, the outer portions of the inseam stitches are higher at the toe end of a shoe than elsewhere, that is to say, they lie at a greater distance above the marginal feather of the insole at the toe end because at this portion of a shoe there are five layers of material superposed upon the marginal feather, while at portions beyond the range of the toe-box there are only three superposed layers. It follows that as the trimming cut progresses from the heel end toward the toe end along one side of the shoe, it may cut the relatively high stitches at the toe end if it is as close as desired to the stitch-line where the stitches are lower.

In the machine illustrated and described in the above-mentioned patent the outer surface of the inseam is guided by a feed-roll that has no movement except rotation, while the inner surface of the inseam is engaged by a channel-guide capable of yielding in response to comparatively thick portions of the seam. Under these conditions, when a comparatively thick portion of the seam is advanced into contact with the feed-roll (immovable, except its rotation) the thick portion is unavoidably crowded against the trimming cutter. Now, since the outer portions of the stitches are higher in the relatively thick portion of the seam, the trimming cutter is likely to attack them unless something is done to relieve them from being crowded against the cutter.

To guard against cutting the stitches at the toe end, skilled operatives have adopted the practice of elevating the heel end of the shoe

and maintaining it at an abnormally high altitude while the relatively thick part of the seam is being trimmed, and thereafter returning it to its normal level. This practice, if perfectly timed and executed, is capable of producing uniformly close trimming, but the raising and lowering of the heel end is not always correctly timed nor of the required amplitude. Consequently, faulty manipulation in this respect usually results in uneven trimming but omission of all such manipulation results sometimes in cutting the outer portions of the high switches.

The chief purpose of the present invention is to provide improvements in machines of the type above mentioned that will insure uniformly close trimming without special manipulation to counteract variations in thickness of inseams and greater height of the stitches in the thicker portions of the seams.

To this end a novel feature of the improved machine herein illustrated and described is that the feed-roll that runs on the outer surface of the inseam is arranged to be capable of yielding away from the channel-guide in response to increments in the thickness of the seam, while the channel-guide is maintained positively in a constant location to compel the feed-roll to yield. The ability of the feed-roll to be displaced avoids the above-mentioned crowding of the thicker portions of the seam against the cutter.

The problem of insuring uniformly close trimming to high and low stitches is solved by another improvement, namely, constraining the feed-roll and the welt-crease guide to receive a component of upward movement as they are displaced by a relatively thick portion of the seam. This component of upward movement is calculated to counteract the curvature of the supplemental arc of the cutting edge that is brought into the field of cutting by the thicker portions of the seam.

From the foregoing it is to be appreciated that the improved features maintain the inner side of the seam in a constant relation to the operating segment of the cutter and, while permitting the outer side of the seam to travel its normal path, maintain the outer stitch-line at a constant distance from the arc of the cutting edge.

Referring to the drawings, Fig. 1 is a front elevation of the head of an inseam-trimming machine embodying the principles of the present invention;

Fig. 2 is an elevation of the rotary channel-guide and transmission gearing for driving it;

Fig. 3 is a perspective view of a section of the suction conduit through which the severed pieces of surplus materials are removed from the cutter;

5 Fig. 4 is a vertical section of the head of the machine as viewed from right to left;

Fig. 4A is a side elevation of a treadle for shifting some of the elements represented in Fig. 4;

10 Fig. 5 is a horizontal section including a portion of the feed-roll carrier and confronting portions of the frame by which it is flanked;

Fig. 6 is a rear elevation of a portion of the head including treadle connections;

15 Fig. 7 is an enlarged scale elevation partly in vertical section including a portion of a welted shoe, the inseam of which is in process of being trimmed; and

20 Fig. 8 is a view similar to Fig. 7 in which a relatively thick portion of the inseam is at the trimming locality.

The construction of the inseam of an ordinary welted shoe is illustrated in Figs. 7 and 8, the latter figure representing the toe portion of a shoe and including a toe-box and a doubler, while 25 Fig. 7 represents another portion of the shoe beyond the range of the toe-box and the doubler. In these figures, the following elements of the work are included: an insole 10, an upper 11, a lining 12, a last 13, a welt 14, a three-ply stitching-receiving rib 15 formed on the insole, and inseam stitches 16. The toe portion of the shoe (Fig. 8) includes two additional elements, namely, a toe-box 17 and a doubler 18. According to this figure, it is apparent that five layers of material 30 are superposed upon the marginal feather 19 of the insole while at other portions of the shoe only three superposed layers are present. A comparison of these views will show not only that the inseam is thicker within the range of the toe-box but also that the outer portions of the stitches 16 are a greater distance above the marginal feather 19 where they lie on five superposed layers than where they lie on only three. The inequalities in the thickness of the inseam 35 and the higher location of the outer portions of the stitches where the inseam is relatively thick create the problems with which the present invention is concerned.

In Figs. 7 and 8, the arcuate line 20 represents 40 a segment of the annular cutting edge of a rotary, tubular trimming cutter of well-known construction. The body of this cutter is indicated at 21 in Figs. 1 and 4. As in former machines of this same general type, the cutter is 45 arranged to rotate about a horizontal axis 22 and for this purpose it is affixed to a shaft 23 journaled in an adjustable bearing fixture 24. The direction of its rotation is indicated by an arrow in Fig. 4. Power-driven means for rotating the 50 cutter comprises the following train of gears, better shown in Fig. 4: a driven gear 25, an intermediate gear 26, an intermediate gear 27, and a driving gear 28. The driving gear is affixed to a shaft 29 provided with a pulley 30 to be driven 55 by a belt 31 (Fig. 1).

A short segment at the bottom of the cutter is used to do the trimming. When the upturned bottom of a welted shoe is presented to this cutting segment, the face of the insole 10 is brought 60 into contact with the lower end of a channel-guide 35. The channel-guide requires no motion so far as its guiding purpose is concerned but since the illustrated machine is of the type that includes power-operated feeding mechanism, the 65 channel-guide is rotated about a fixed axis to

supplement the feeding effect of a power-driven feed-roll hereinafter described. Accordingly, the channel-guide is of circular cross section and is affixed to the lower end of a spindle 36 (Fig. 2). The spindle is journaled in a support or bearing member 37 suspended from the frame 59 by a horizontal bushing 32 and a trunnion 39. The support 37 also provides a bearing for a transmission shaft 40 by which rotation is transmitted to the channel-guide, the driving 10 connection between this shaft and the spindle 36 being provided by pinions 41 and 42 (Fig. 2). A bevel gear 43 affixed to the upper end of the shaft 40 receives rotation from a similar gear 44 affixed to a shaft 38 journaled in the bushing 15 32. This shaft is also provided with a bevel gear 45 (Fig. 1) that receives rotation from a gear 46. Gears 46 and 47 (Fig. 4) both affixed to a transmission shaft 48 receive rotation from a bevel gear 49 that rotates with the gear 27 and 20 is connected thereto by a shaft 50.

For assembling purposes, the bearing member 37 may be swung about the axis of the shaft 38, but when the parts are completely assembled in their operative relations, this bearing member is 25 locked against all movement. For this purpose, its upper portion 51 (Fig. 4) is provided with a socket to receive a locking stud 52 that projects from an adjustable fixture 53. The member 53 is mounted on the bushing 32 and extends to the 30 rear of the machine for connection with anchoring means by which it may be adjusted for the purpose of locating the channel-guide 35 at the desired position. The anchoring means (Fig. 4) comprises a short screw-threaded rod 54, adjusting nuts 55, a sleeve 56, a set-screw 57 by which the rod 54 is secured to the sleeve, and a set-screw 58 by which the sleeve is secured in a socket formed in the frame or head 59 of the machine. The desired adjustment of the channel-guide 35 40 is obtained by adjusting the nuts 55 up or down on the rod 54 and setting them up tightly against the interposed portion of the member 53. The channel-guide is thus maintained rigidly against all movement except rotation with its supporting spindle 36.

While the lower end of the channel-guide abuts the surface of the insole 10 to control the closeness of trimming the inseam at the inner side thereof, the knurled or toothed flange 60 50 thereof maintains the inner surface of the seam in a constant relation to one extremity of the cutting segment of the cutter, and the inner portions of the inseam stitches 16 are maintained slightly below the cutting segment. 55

A feed-roll 61 of well-known construction cooperates with the channel-guide to grip the inseam and to feed the work, but this feed-roll, instead of having a fixed location as in former machines, is provided with an improved mounting by which it is rendered capable of moving toward and from the channel-guide in response to variations in the thickness of the inseam. As shown in Figs. 7 and 8, this feed-roll is concave at its upper end to clear a non-cutting segment 65 of the trimming cutter and is provided with an external frusto-conical welt-engaging band 62 on which teeth or ridges are formed to insure a powerful work-feeding effect. The rim 63 of the feed-roll is thin and is arranged to engage 70 the outer portions of the stitches 16 while the toothed band 62 bears on the outlying margin of the welt that projects laterally from the stitches.

The feed-roll 61 is affixed to the upper end of 75

an inclined shaft 64 (Fig. 4) journaled in a movable bearing member 65. Rotation for operating the feed-roll is transmitted to the shaft 64 from the shaft 29 by a train of connections comprising a worm 66, a worm-wheel 67, a shaft 68, a helical gear 69, and a helical gear 70. The intermeshed relation of the gears 69 and 70 is such as to permit limited movement of the gear 70 toward the front and rear of the gear 69 without disturbing their operation. Such movement of the gear 70 is incidental to the to-and-fro movements of the feed-roll in response to variations in the thickness of the inseam.

The movable bearing member 65 is supported by a bar 71 to which it is affixed by a pin 72. This bar is arranged to slide lengthwise in fixed bearings 73 in the frame 59. To prevent rocking movement of the bearing member 65 about the axis of the bar 71 the lower portion of the bearing member is arranged between two flat, parallel, confronting cheeks 74 of the frame 59 (Fig. 5). Two flat bearing faces 33 formed on the member 65 engage and slide on these cheeks as the bar 71 slides in its bearings 73. This movable assemblage is spring-biased toward the channel-guide 35 by a compression spring 75 that surrounds the bar 71 and is located between a fixed abutment 76 and a collar 77 fastened to the bar.

It is to be observed that the bar 71 is inclined and that its inclination has the effect of producing a component of upward movement of the feed-roll 61 as the latter recedes from the channel-guide. This component of upward movement is calculated to equalize the distance from the axis of the cutter 21 to the nip of the feed-roll 61 at both limits of its to-and-fro travel corresponding to the maximum range of variation in the thickness of an inseam. Consequently, although the cutting edge 20 is circular while the line of to-and-fro travel (see broken line 78 in Fig. 8) of the nip of the feed-roll is rectilinear, this range of travel will be, to all intents and purposes, parallel with that arc of the cutting edge that corresponds to the range of travel. The objective result is that the nip of the feed-roll will insure uniform closeness of trimming with respect to the stitchline at the outer side of the seam, regardless of variations in the thickness of the seam. Broken line 79 in Fig. 8 represents the location of the axis of the feed-roll when the latter is repelled by a thick portion of the inseam, and broken line 80 represents the location of the same axis when a thin portion of the inseam permits the feed-roll to advance.

A welt-crease guide 81 of well-known construction is arranged to co-operate with the band 62 of the feed-roll to grip the outlying margin of the welt, but, instead of being maintained in a constant location during operation, as in former machines, it is mounted, for the purposes of the present invention, to partake of the to-and-fro movements of the feed-roll. The guide 81 is a freely rotatable roll or disk and is supported by a lever 82 (Fig. 4) to which it is connected by a pivot stud 83. The lever 82 is mounted on the movable bearing member 65 to which it is connected by a fulcrum pin 84. This connection provides for depressing the welt-crease guide 81 to facilitate inserting the welt between it and the feed-roll. A tension spring 85 maintains a downward pull on the rear end of the lever 82 to press the crease-guide 81 firmly against the welt.

The illustrated machine includes a treadle 86

(Fig. 4A) and compound connections by which a simple downward movement thereof will retract the crease-guide 81 from the feed-roll 61 and thereafter retract both the crease-guide and the feed-roll from the channel-guide 35. Although the scale of Fig. 4A is smaller than that of Fig. 4 the relation of these views will serve well enough to illustrate the actual relation of the parts. The treadle is connected to the pedestal of the frame structure by a fulcrum pin 87 and is normally maintained in an elevated position by a tension spring 88. A rod 89 connected to the treadle extends upwardly through the frame and is provided with a striker 90 affixed thereto by a set-screw 91. The striker is also bored to receive a guiding rod 92 (Fig. 6) to which it is secured by a set-screw 93. The rod 92 is arranged to slide in a guiding boss 94 formed on the frame 59, and has no connection with the threaded rod 54 that appears in line 20 therewith in Fig. 4. When the treadle-rod 89 is depressed, the striker 90 carried thereby depresses a roll 95 mounted on a lever 96, and the lever is thereby rocked on its fulcrum pin 97. A roll 98 carried by another arm of the lever is thereby raised against the rear arm of the lever 82 with the result that the welt-crease guide 81 is depressed.

If the treadle-rod 89 be further depressed after it has depressed the welt-crease guide, it will retract the carrier 65, 71 from the channel-guide 35. For this purpose, the lever 96 is provided with a tappet 99 that will, after traveling some distance, strike and depress an arm 100 of a bell-crank lever that comprises another arm 101. 35 This bell-crank lever is also mounted on the fulcrum pin 97, and the arm 101 is formed and arranged to straddle the rod 71 and to displace the collar 77 against the applied force of the compression spring 75. Through these connections, the first stage of movement of the treadle 86 merely depresses the welt-crease guide 81 but the final stage of such movement retracts both the welt-crease guide and the feed-roll. 40

A suction conduit for removing severed pieces 45 of surplus material from the cutter comprises a stationary section 102 (Fig. 1), an intermediate section 103 and a receiving nozzle 104 (Fig. 4). The receiving nozzle is mounted on the bearing member 65 and partakes of the to-and-fro motions of the latter. Consequently, to avoid interference with such motion, the nozzle 104 and the intermediate member 103 are provided with flat abutting faces that lie in a vertical plane parallel with the path of movement of the 50 nozzle. The vertical abutting face of the intermediate member 103 is indicated at 105 in Fig. 3. This intermediate member is also provided with a hinge formation 106 complementary to a corresponding hinge formation 107 on the frame 59. 55 The hinge construction provides for swinging the member 103 away from the cutter to clear out large chips that may become clogged. The members 102 and 103 are therefore provided with 60 abutting flat faces that permit the described 65 movement of the hinged member and close the suction passageway when the parts occupy their operative positions.

Having thus described my invention what I claim as new and desire to secure by Letters Pat- 70 ent of the United States is:

1. In an inseam-trimming machine of the type in which the materials forming the inseam of a welted shoe are gripped and guided to the cutting segment of a rotary tubular cutter by a 75

- channel-guide and a welt-engaging feed-roll while the outlying margin of the welt is guided by confronting the portions of said feed-roll and a welt-crease guide, the improvements comprising 5 means by which said channel-guide is secured in a constant position adjacent to said cutting segment, spring-biased means including a movable bearing by which said feed-roll is carried to and fro in response to variations in the thickness of 10 the inseam and constrained to maintain a work-feeding grip thereon, and power-driven means arranged to operate said feed-roll in its various positions.
2. An inseam-trimming machine as specified 15 in claim 1 in which said spring-biased means is arranged to equalize the distance from the axis of said cutter to the nip of said feed-roll at both limits of its to-and-fro travel corresponding to the range of variation in the thickness of the 20 inseam.
3. An inseam-trimming machine as specified in claim 1 in which said welt-crease guide is also carried by said spring-biased means to partake of the to-and-fro motions of said feed-roll in 25 response to variations in the thickness of the inseam.
4. An inseam-trimming machine as specified in claim 1 in which said welt-crease guide is carried by an individually movable spring-biased 30 means carried by the spring-biased means first mentioned and thereby constrained to press the outlying margin of the welt against said feed-roll.
5. An inseam-trimming machine as specified

in claim 1 comprising a treadle and connections operable thereby to retract said welt-crease guide from said feed-roll and to retract both the welt-crease guide and the feed-roll from said channel-guide.

5

6. An inseam-trimming machine as specified in claim 1 in which said channel-guide is a roll maintained on a fixed axis of rotation, and comprising power-driven means arranged to rotate it in a direction to supplement the feeding 10 effect of said welt-engaging feed-roll.

7. An inseam-trimming machine comprising a tubular cutter arranged to rotate about a horizontal axis and having an annular cutting edge, a channel-guide maintained in a constant location adjacent to the lowest point of said cutting edge to be engaged by the upturned bottom of the insole and by the inner surface of the inseam of a welted shoe, a welt-crease guide, a feed-roll formed and arranged to co-operate with 20 said channel-guide to grip the inseam at the stitch-line and with said welt-crease guide to grip the outlying margin of the welt, a carrier by which said welt-crease guide and said feed-roll are carried toward and from said channel-guide, 25 means by which said carrier is constrained to impart a component of upward movement to said feed-roll and said welt-crease guide as they recede from said channel-guide, resilient means arranged to maintain pressure of said feed-roll 30 against the inseam, and power-driven means arranged to rotate said feed-roll.

JOHN M. WHELTON.
